NOZZLE

Lars Ell, Stockholm, Sweden, assignor to Electrolux Corporation, Dover, Del., a corporation of Delaware

Application November 6, 1934, Serial No. 751,714
In Germany November 8, 1933

5 Claims. (Cl. 15—158)

My invention relates to nozzles for vacuum cleaners and particularly to elongated nozzles provided with brush bristles. Circular nozzles of this type are known in which the bristles are supported interiorly by means of a spherically shaped member made of resilient material. The spherical shape of the resilient member makes it capable of resisting the tendency to collapse which is imposed upon it by reason of the partial vacuum maintained therein by the vacuum cleaner. However, I have found that in an elongated nozzle such collapse will take place and the inlet opening in the bottom of the resilient member will be sucked together unless means are taken to prevent it.

One of the objects of my invention is to provide suitable means for preventing the closing of the inlet opening due to the effect of suction.

Further objects and advantages of my invention will be apparent from the following description considered in connection with the accompanying drawing, which forms a part of this specification, and of which:

Fig. 1 is a bottom view of one embodiment of my invention;

Fig. 2 is a cross-sectional view, taken on the line 2—2 of Fig. 1;

Fig. 3 is a cross-sectional view, similar to Fig. 2, showing a second embodiment of my invention; and

Fig. 4 is a cross-sectional view showing a third embodiment of my invention.

Referring more particularly to Figs. 1 and 2, reference character 10 designates an elongated base member made of rigid material, such as metal, wood or "Bakelite". Base member 10 is formed with an elongated opening 11 therethrough. An elongated hollow member 12 of resilient material, such as soft rubber, is made with an upper flange 13, which extends across the solid part of base member 10. Formed integral with flange 13 is a flared portion 14, the upper part of which extends through the opening 11 in base member 10 and the lower part of which extends below the base member. Hollow member 12 is formed with a lower elongated inlet opening 15. In order to prevent the drawing together of the material of the hollow member around opening 15, the hollow member is formed with a bead 16, which is reenforced. In the embodiment shown in Fig. 2, the reenforcing is obtained by vulcanizing this bead especially hard. This gives sufficient stiffening to the sides of opening 15 to prevent closure of the opening due to the effect of suction.

A hose connection member 17 is secured to base member 10 by means of bolts 18. Flange 13 of the hollow member extends between the base member and member 17 and acts as a packing to prevent the leakage of air therebetween. The outer edge of flange 13 may be formed so as to embrace the outer edge of base member 10, as is shown at 19, in order to provide a soft surface for preventing the marring of furniture if the nozzle is accidentally brought into contact therewith.

A plurality of groups of brush bristles 20 are suitably secured to the under side of base member 10 and extend downwardly therethrough around the outside of hollow member 12. The hollow member serves to support these bristles and to prevent them from being drawn together by the suction.

In operation, a conduit is connected to member 17 and to a source of suction, such as a vacuum cleaning apparatus. Consequently, a reduced pressure is produced within hollow member 12 and air is drawn therewith through lower inlet 15. If the nozzle is passed over a dusty surface, the bristles serve to loosen the dust, which is then picked up by the air stream and carried to the vacuum cleaner. As has been previously explained, the reenforcing of bead 16 prevents the closing of the opening 15 due to the effect of suction.

The embodiment shown in Fig. 3 is similar to that shown in Fig. 2, with the exception that the bead 16 is formed with a slot or groove 21 in which is placed a stiff wire 22. Wire 22 serves to reinforce the resilient member around the opening 15 and thus serves to prevent closing of the opening.

In the embodiment shown in Fig. 4, the hollow member 12 is secured in a groove 23 formed in a portion 24 depending from the base member 10. In this embodiment a reinforcing wire is cast in the bead 16 when the hollow member is made.

If during cleaning the nozzle should be pressed too hard against the surface to be cleaned it may happen that the bristles, if made of too soft material, are bent outwardly so that the bottom of the resilient hollow member 12 may come into close contact with the surface to be cleaned. In order to prevent the hollow member from adhering to the surface due to the partial vacuum maintained in the member it is preferable that the greatest interior width of the hollow member, designated *a* in Fig. 4, be at least twice as great as the width *b* of opening 15. This proportioning of the hollow member allows the bot-

tom of the hollow member to be lifted inwardly due to suction effect, thus freeing the nozzle from the surface.

While I have shown and described three more or less specific embodiments of my invention, it is to be understood that this has been done for purposes of illustration only, and that my invention is not to be limited thereby, but is to be given the broadest interpretation commensurate with the appended claims, viewed in the light of the prior art.

What I claim is:

1. In an elongated suction nozzle, a rigid base member formed with an opening therethrough, a suction conduit communicating with said opening, an elongated hollow member of resilient material depending from said base and having its interior in communication with said opening, said hollow member being formed with a lower elongated inlet opening, a rigid reinforcing member extending around the inlet opening of said hollow resilient member for preventing the closing of said inlet opening due to the effect of suction, and bristles secured to said base member and extending downwardly therefrom around, and supported laterally by, said hollow member.

2. In an elongated suction nozzle, a rigid base member formed with an opening therethrough, a suction conduit communicating with said opening, an elongated hollow member of resilient material depending from said base and having its interior in communication with said opening, said hollow member being formed with a lower elongated inlet opening, a rigid member cast in the material of said hollow member around the inlet opening thereof for preventing the closing of said inlet opening due to the effect of suction, and bristles secured to said base member and extending downwardly therefrom around, and supported laterally by, said hollow member.

3. In an elongated suction nozzle, a rigid base member formed with an opening therethrough, a

suction conduit communicating with said opening, an elongated hollow member of resilient material depending from said base and having its interior in communication with said opening, said hollow member being formed with a lower elongated inlet opening, said hollow member being formed with a slot therein around said inlet opening, a rigid member in said slot for preventing the closing of said inlet opening due to the effect of suction, and bristles secured to said base member and extending downwardly therefrom around, and supported laterally by, said hollow member.

4. In an elongated suction nozzle, a rigid base member formed with an opening therethrough, a suction conduit communicating with said opening, an elongated hollow member of resilient material depending from said base and having its interior in communication with said opening, said hollow member being formed with a lower inlet opening, the greatest interior width of said hollow member being at least twice as great as the width of said inlet opening, and bristles secured to said base member and extending downwardly therefrom around, and supported by, said hollow member.

5. In an elongated suction nozzle, a rigid base member formed with an opening therethrough, a suction conduit communicating with said opening, an elongated hollow member of resilient material depending from said base and having its interior in communication with said opening, said hollow member being formed with a lower inlet opening, the greatest interior width of said hollow member being at least twice as great as the width of said inlet opening, a rigid reinforcing member extending around the inlet opening for preventing the closing of said inlet opening due to the effect of suction, and bristles secured to said base member and extending downwardly therefrom around and supported by, said hollow member.

LARS ELL.
